UNITED STATES PATENT OFFICE.

RICHARD H. GRIFFITH, OF RICHMOND, INDIANA, ASSIGNOR TO THE OHIO CULTIVATOR COMPANY, OF BELLEVUE, OHIO, A CORPORATION OF OHIO.

CULTIVATOR.

Application filed March 19, 1925. Serial No. 16,702.

This invention relates to cultivators designed to cultivate the soil in fields having growing crops of corn.

The first and major object of the invention is to so combine a seat frame with the cultivator beams that when the beams are permitted by the driver to yield to the lifting action of certain springs, which adds material weight back of the axle, the seat frame will bodily move forward to transfer a part of its weight and that of the driver to points forward of the axle, whereby to counterbalance the weight added at the rear of the axle by reason of the elevation of the beams; and whereby also when the beams are placed by the driver in cultivating position, with their shovels in the ground sustaining their weight, thus lessening the weight on the machine at the rear of the axle, the seat frame will then move rearwardly to restore the balance of the machine to what may be regarded as normal.

A further object in carrying out this general combination is to connect the seat frame with the main frame by means of swinging links, and to connect the rods by which the beams are suspended and lifted to some of such links, and to provide springs fixedly anchored at one end and connected at their other end to such links to act on the beams in a manner to draw upward on them as the seat frame is moved forward and to yield and allow the beams to descend as the seat frame is moved rearwardly.

A further object is to combine with one pair of the seat frame links a lever-like cross bar carrying a pivoted yoke to which the beam-supporting rods are attached in a yielding manner, so that as the beams are lifted by the rods the seat frame will be advanced forwardly; and vice versa, when the beams are lowered the seat frame will be moved rearwardly.

And a still further object is to combine with the links, yoke and rods arranged as above stated, springs attached at one end to the general frame and at the other to extensions on the links so as to act in a direction to lift on the beams when they are to be elevated, and thereby to relieve the driver

from excessive labor in lifting the beams and forwardly advancing the seat frame.

To the above several objects may be added numerous features of detail which will hereinafter appear in the body of the specification.

In the accompanying drawings:

Figure 1 is a plan view of my cultivator as a whole. 60

Figure 2 is a perspective view thereof, looking from the rear toward the front of the machine.

Figure 3 is a side elevation of the machine with the seat frame in its forward position and the shovel beams in their elevated position, as when not in operation. 65

Figure 4 is a like view to Figure 3 but with the seat frame in its rear position and the beams in their lowered or operating position with the shovels acting in the ground. 70

Figure 5 is a detail view showing two of the seat frame links, the yoke supported thereby and beam lifting rods actuated by the yoke. 75

The numeral 1 indicates a pair of ground wheels mounted on the spindles that project from an arched axle 2. Secured to the axle is a general frame in the nature of a draft frame comprising side bars 3 secured at one end to the arched axle as by clips 4, with a cross bar 5, and at their forward ends to a draft pole 6 through a bolt 7. A cross bar 8 is secured to the side bars 3 of the draft frame and the pole is also attached to this cross bar by means of a plate 9 through bolts 10, such plate being secured to the cross bar 8 by other bolts 11. 80

To this cross bar 8 are attached brackets 12 which in turn are connected with the arch through brace rods 13 and which carry a cross shaft 14 on which are mounted the couplings 15 in a manner to turn on the shaft when the beams are raised and lowered. The 85 beams are connected to these couplings. The beams may be of any conventional type but are preferably made each of a pair of bars 16 suitably braced together and both equipped with clamps 17 which carry conventional standards 18 to which the usual shovels are attached. The beams are further equipped 100

with draft hooks 19 connected with draft links 20 to which is attached a draft tree 21. In this way the draft strains are applied to the arch through the links 13 and the connections described and also applied directly to the beams through the hooks 19, links 20 and tree 21.

The features so far described are essentially conventional.

10 I will now refer to the features which enter into this preferred form of construction by which my invention is carried into effect. These comprise the forward links 22 pivoted at 23 to the side bars 3 of the main or draft frame. These links have extensions 24 provided with a series of notches for connection with springs 25 whose other ends are anchored to the arch or main frame by projections 26 extending from the clips 4. The function of these springs is to aid in lifting the shovel beams by drawing rearwardly on the link extensions and forwardly on the other ends of the links 22 which has the effect of elevating the yoke 27 which 25 is attached to a cross bar 28 that extends from one link 22 to the other. The yoke is pivoted at 29 and at its end is provided with openings through which extend beam rods 30 which at their lower ends are hooked to the 30 beams and at their upper portions are equipped with adjustable collars 31, one collar above the yoke and one below on each rod. Coil springs encircle the rods, one spring 32 between the lower collar and the 35 yoke and another spring 33 between the upper collar and the yoke, on each rod. The function of these springs is to permit the two rods to yieldingly slide through the openings in the yoke; and the particular 40 function of the upper springs is to allow the rods to yield downward when the beams are being depressed to working position and to react and lift on the rods when the beams are being elevated and thus aid in the effort of 45 the driver to lift the beams.

The purpose in pivoting the yoke 27 to the cross bar 28 is to aid the driver in letting one beam down further than the other if cultivating on an incline, as a hillside. And 50 it will be noted too that the cross bar 28, at the part where the yoke is pivoted thereto, is set considerably back or to one side of the pivots 23 of the links 22, which constitutes a sort of lever of this bar 28 which has 55 the effect of tending to turn these links on their centers and to cause their extensions to create a tension on the beam-lifting springs 25, whereby these springs act through the links, the bar 28, yoke 27, and rods 30 to 60 suspend the beams in what may be called a floating manner, as indicated in Figure 3. Again, when the driver lifts on the handles 34 to raise the beams, these springs 25 through their contracting action materially 65 aid in elevating the beams; or, indeed, prac-

tically lift them if their tension is adjusted high enough for that purpose, which may be done through the hooks 35 which connect the springs with the clips 4 and are adjustable through the nuts 36.

It will now be seen that the beams are or may be suspended by the action of the springs 25 operated through the links 22 and the connection of the yoke therewith and of the beam rods 30, and that when the beams are depressed by the driver through the handles 34 and the stirrups 37 (either or both), the springs 25 will expand and permit this action, and will lift more or less on the beams while the shovels are in the ground, leaving it to the option of the driver to depress the shovels more or less by the pressure he exerts on the beams through the stirrups, or if need be in particular cases, through the handles also.

Referring now to the seat frame, it will be seen that it comprises side bars 38 which converge toward their rear ends to which the seat extensions 39 are secured by a pivot bolt 40. A stop pin 41 may be adjusted into either of the holes 42 so as to adjust the forward end of the extension 39 up or down to lower or raise the seat 43. The seat and its extensions may be thrown forward past and above the frame bars 38 by turning the extension 39 on the bolt 40, a feature of convenience when the machine is to be stored in an implement shed when not in use or is to be shipped.

The forward ends of the seat bars 38 are turned upward to properly position them to be pivoted to the links 22 by clips or bolts 22. Further rearward the seat frame bars are provided with brackets 44 to connect the bars pivotally with the rear links 45 through pivot bolts 46. These links 45 are pivoted to the main frame or arch through a rock shaft 47 carried by bearings 48 extending from the clips 4. But any other form of pivotal connection between the general frame and these links 45 may be used.

It will now be seen that the seat frame is pivotally supported on the main or draft frame and is capable of being adjusted forwardly or rearwardly so as to increase the weight on the main frame forward of the axle and thereby decrease it at the rear thereof, or to increase it at the rear and thereby decrease the weight forward thereof. It will further be noted that, by reason of the connections described between the beams and the seat frame, namely the forward links, the lever-like cross bar 28, the yoke 27 and the beam rods 30, the seat frame and beams move in unison—the frame forwardly when the beams are raised and rearwardly when the beams are depressed, so that when the beams are in their highest or elevated position the seat frame is in its most for-

ward position, and when the beams are in their lowest or cultivating position, the seat frame is in its furthest rearward position.

In effecting these movements and changes 5 of position the beam-lifting springs 25 function in aid of elevating the beams and positioning the seat frame forwardly, yet permit the reverse of these movements of the beams and seat frame.

10 While I prefer to connect the seat frame to the general frame by means of the swinging links described, still I wish to be understood as not limiting myself to such a means of connection between the two frames so long as there is preserved such interconnection 15 between the seat frame and the beams as that when the driver causes or permits the beams to raise, the seat frame will advance forwardly by reason of connections between it and the beams; and vice versa, when the driver returns the beams to the ground he will thereby, through the connections between the beams and the seat frame, cause the seat frame to 20 assume its rearward position.

In my Patent No. 1,576,650 dated March 16, 1926, and in my later application, Serial No. 13,717 filed March 7, 1925, I have shown and described seat frames adjustable forwardly to lift the beams and rearwardly to let the beams down, the seat frame itself being the part primarily actuated for that purpose by means of a lever operated to move the seat frame to its different positions and in doing so to raise and lower the beams, the seat frame itself being the manually operated element. But in the present case the beams are the elements which are operated and whose movements effect the 30 movements of the seat frame. So that in the former applications the seat frame operated the beams, while in the present application the beams operate the seat frame. I regard myself to be the first to accomplish 40 this latter operation with its resulting advantages and efficiency in the practical use of cultivators.

In order to adjust the couplings 15 with their beams nearer to, or further from, each other I provide a lever 1^a pivoted to a bracket 2^a secured to the rod 14 and having links 3^a which connect with the couplings 15 to so adjust them. A series of perforations 4^a in the bracket 2^a are adapted to receive one end of one of the links 3^a in order to lock the lever 1^a in adjusted positions. This is not a feature of the present invention but is one I prefer to use.

Having thus fully described my invention, what I claim as new and desire to secure by Letters Patent, is:

1. In a cultivator, the combination with a wheeled draft frame and shovel beams carried thereby and adapted to act as means for positioning the seat frame, of a seat frame,

and connections between the seat frame and such beams whereby such frame is advanced forwardly when the beams are raised and rearwardly when the beams are lowered, such connections including springs which act in 70 one direction to lift on the beams and in the other direction to permit the beams to be lowered.

2. In a cultivator, the combination with a 75 wheeled draft frame and shovel beams carried thereby and adapted to act as means for positioning the seat frame and means by which the beams may be elevated and lowered, of a seat frame, links which connect said frame to the main frame and permit it 80 to move forwardly and rearwardly, and connections between some of the links and the beams whereby such frame is advanced forwardly when the beams are raised and rearwardly when the beams are lowered. 85

3. In a cultivator, the combination with a 90 wheeled draft frame and shovel beams carried thereby and adapted to act as means for positioning the seat frame, of a seat frame, links which connect said frame to the main frame and permit it to be moved forwardly and rearwardly, and connections between some of the links and the beams whereby such frame is advanced forwardly 95 when the beams are raised, and rearwardly when the beams are lowered, and springs connected to the main frame and to such links and acting to exert an elevating force on the beams and at the same time a forward movement on the seat frame. 100

4. In a cultivator, the combination with a 105 wheeled main frame and beams connected thereto, of a seat frame, links which connect the seat frame with the main frame, a lever-like member connected with the link structure, and connections between such member and the beams, whereby when the beams are elevated the lever-like member is operated and the link structure is caused to move the seat frame forwardly. 110

5. In a cultivator, the combination with a 115 wheeled main frame and beams connected thereto, of a seat frame, links which connect the seat frame with the main frame, a lever-like member connected with the link structure, connection between such member and the beams, and springs connected to the main frame and to the link structure and adapted to exert a lifting force on the beams, whereby when the beams are elevated the lever-like member is operated and the link structure is caused to move the seat frame forwardly. 120

6. In a cultivator, the combination with a 125 wheeled main frame and beams connected thereto, of a seat frame, links which connect the seat frame with the main frame, a yoke having a lever-like connection with one pair of said links, and connections between such yoke and the beams, whereby when the beams are elevated the yoke is actuated and such 130

pair of links are operated to cause the seat frame to move forwardly.

7. In a cultivator, the combination with a wheeled main frame and cultivator beams carried thereby, and having handles, of a seat frame, links pivotally connecting the seat frame with the main frame, a lever-like member extending from two of the links, rods which connect with said member and with the beams, and springs which exert a lifting force on said pair of links and cause them, through their connections with the beams, to lift the beams and also cause them to advance the seat forwardly.

15. 8. In a cultivator, the combination with a wheeled main frame and beams carried thereby and having handles and stirrups, of a seat frame having a seat at one end, links pivoted to the main frame and to the other end of the seat frame, one pair of such links having a lever-like member, a yoke pivoted to such member, rods yieldingly connected with said yoke and attached to the beams, and springs anchored to the main frame and connected with said lever-like member through said pair of links, whereby said lever-like member is caused to lift on the beams through said connections and

whereby said pair of links are caused to then advance the seat frame forwardly.

30 9. In a cultivator, the combination with an arched wheeled frame, a cross shaft thereon, beams coupled to said shaft and adapted to be raised and lowered and having handles and stirrups, of a seat frame having a seat positioned near said handles, links pivoted to the main frame and to the seat frame, one pair of the links having a lever-like member, a yoke pivoted thereto, rods slidably mounted in the yoke and attached to the beams, stops on said rods and springs between the stops and the yoke, and lifting springs attached to the main frame and to extensions on said pair of links, all for the 35 purpose described.

40 10. In a cultivator, the combination with a main frame, of a pair of links pivoted to the frame and having portions which extend above and below the pivots, a lever-like cross-bar connected to said links and extending rearwardly, and a yoke pivoted to the lever-like bar and adapted at its ends to be 45 connected to beam-lifting rods.

50 In testimony whereof, I affix my signature.

RICHARD H. GRIFFITH.
